UNITED STATES PATENT OFFICE.

HENRY JAMES BROOKE, OF SVENDBORG, DENMARK.

SHIP'S ANCHOR.

SPECIFICATION forming part of Letters Patent No. 721,663, dated March 3, 1903.

Application filed July 1, 1902, Serial No. 114,026. (No model.)

To all whom it may concern:

Be it known that I, HENRY JAMES BROOKE, retired engineer, a citizen of Great Britain, residing at Svendborg, Island of Tunen, in the 5 Kingdom of Denmark, (whose post-office address is 49 Vimmelskaftet, Copenhagen, Denmark,) have invented certain new and useful Improvements in Ships' Anchors; and I do hereby declare the following to be a full, clear, 10 and exact description of the invention, such as will enable others skilled in the art to which it appertains to make and use the same, reference being had to the accompanying drawing, and to letters of reference marked there- 15 on, which forms a part of this specification.

The present invention refers to improvements in ships' anchors; and its subject is an automatic stockless four-armed anchor in which one pair of arms is rigidly fastened to 20 the shank, while the other pair is arranged so as to be capable of moving up the lower part of the shank, which is formed like a screw with a great pitch. The length of the screwed part of the shank and the pitch are 25 arranged in such a manner that the movable pair of arms will shift from a cross position when resting on the fixed pair of arms to a parallel position after having made one-fourth of a revolution in moving from the 30 cross position to the extremity of the screwed part of the shank. The advantage of this arrangement is that the anchor is capable of lying flat down on the deck and of automatically assuming the cross position when 35 heaved overboard, so that at least two flukes must take hold.

The invention is illustrated in the accompanying drawing, showing an anchor of the described type seen from above as lying on 40 deck, with the two pairs of arms parallel to one another.

a is the shank; *b*, the fixed pair of arms; *c*, the movable pair.

The lower part of the shank *d* is shaped 45 like a screw with great pitch, on which the boss *e* of the movable pair of arms *c*, like a nut, is capable of turning. The screwed

part *d* of the shank, which is preferably made slightly conical from the base upward, can be formed simply by twisting a square bar. 50 A fixed collar *h* on the shank limits the movement of the movable pair of arms. The fixed pair of arms is attached in a suitable manner to the lower extremity of the shank, which is also provided with a ring *f*. The upper 55 extremity of the shank is provided with a ring *g* in the usual manner.

Having thus fully described my invention, what I claim as new, and desire to secure by Letters Patent, is—

1. In an anchor, a shank having a spirally-disposed guideway upon its lower end and a pair of arms rigidly secured to the end of the shank in combination with a pair of movable arms having an aperture adapted to loosely 65 receive said shank and move upon said guideway whereby when both pairs of arms are in contact with each other they will be disposed at right angles and when said movable arms are moved up the shank in said guideway 70 they will be turned by said guideway and disposed substantially parallel with the fixed arms as and for the purpose set forth.

2. The herein-described anchor comprising a shank having a spirally-disposed guideway 75 upon its lower end; a pair of arms fixedly secured to the extreme lower end of the shank and a pair of movable arms disposed around said shank in coöperation with said guideway whereby when the arms are in contact with 80 each other they will be substantially at right angles and when said arms are separated they will occupy substantially the same plane and means carried by the shank to connect it with the cable all substantially as specified and 85 for the purpose set forth.

In testimony that I claim the foregoing as my invention I have signed my name in presence of two subscribing witnesses.

HENRY JAMES BROOKE.
